UNITED STATES PATENT OFFICE.

JOHN B. VAN HOUTEN, OF NEWARK, NEW JERSEY.

DESIGN FOR AN EAR-RING AND PENDANT.

SPECIFICATION forming part of Design No. 14,520, dated December 25, 1883.

Application filed July 13, 1883. Term of patent 7 years.

To all whom it may concern:

Be it known that I, JOHN B. VAN HOUTEN, a citizen of the United States, residing at Newark, in the county of Essex and State of New Jersey, have invented and produced a new and original Design for Ear-Rings and Pendants; and I do hereby declare the following to be a full, clear, and exact description of the same, such as will enable others skilled in the art to which it appertains to make and use the same, reference being had to the accompanying drawings, and to letters of reference marked thereon, which form a part of this specification.

15 In said drawings, Figure 1 is a front elevation, and Fig. 2 an end view, of my new design, which figures are deemed sufficient to illustrate the same.

20 The leading feature of this design is the peculiar formation and arrangement of the pendant and drop, as will be hereinafter set forth, and embodied in the claim.

In said drawings, the parts A, B, and C are not peculiar features of this design.

The pendant and drop D E F G has the following configuration: The portion D is loop-shaped, and beneath this portion the pendant is band-shaped, the surface E being convex and flaring outwardly toward an indented or scalloped lower edge. From beneath this lower edge, at the sides of the design, projections F curl upwardly over toward the flaring surface. Beneath the flaring band at G the pendant is globular.

What I claim is

In a design for an ear-ring, the design for a pendant and drop, herein shown and described.

In testimony that I claim the foregoing I have hereunto set my hand this 19th day of June, 1883.

JOHN B. VAN HOUTEN.

Witnesses:

OLIVER DRAKE,
F. F. CAMPBELL.
